UNITED STATES PATENT OFFICE.

CLARENCE H. BILLINGS, OF JACKSONVILLE, FLORIDA.

RATCHET IMPLEMENT.

No. 838,000.

Specification of Letters Patent.

Patented Dec. 11, 1906.

Application filed April 17, 1906. Serial No. 312,275.

To all whom it may concern:

Be it known that I, CLARENCE H. BILLINGS, a citizen of the United States, residing at Jacksonville, in the county of Duval and State of Florida, have invented a new and useful Ratchet Implement, of which the following is a specification.

This invention relates to improvements in ratchet implements—such as drills, screw-drivers, boring implements, socket-wrenches, and the like—and has for its object to improve the construction and increase the efficiency of devices of this character.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

In the drawings, Figure 1 is a side elevation of the improved implement applied to a screw-driver. Fig. 2 is a section on the line 2 2 of Fig. 1. Fig. 3 is a side elevation, partly in section, of the improved implement applied to a drill-stock or like implement. Figs. 4 and 5 are views of two of the attachments which may be alternately employed with the structure shown in Fig. 3. Fig. 6 is a side view of a socket adapted to be employed with the structure shown in Fig. 3. Fig. 7 represents the different parts of the operating-handle in perspective and disconnected.

The improved implement herein described may be readily applied to screw-drivers, drill-stocks, boring implements, and the like and for the purpose of illustration is shown in Figs. 1 and 2 applied to a screw-driver and in Fig. 3 applied to a conventional stock for a drill or boring implement.

In the improvement is embraced a toothed disk or enlargement 10, applied to the stock of the implement. In Fig. 1 the toothed member is shown attached to the stock 11 of an ordinary screw-driver, and in Fig. 3 the toothed member is shown applied to a conventional stock 12 of a conventional boring or drilling implement. The member 10 may be formed integral with the stock with which it is associated or formed separately and at-

tached thereto in any suitable manner and is preferably formed with spaced teeth of uniform size and shape upon both sides, so that the implement may be rotated in any direction, as hereinafter shown. The improved device also embraces a detachable handle adapted to be disposed upon the stock and provided with a pawl adapted to engage the teeth of the member 10, and thus enable the stock to be forcibly rotated intermittently. The operating-handle is provided with open recesses adapted to fit over the stock at the opposite sides of the member 10, as shown, with the tooth-engaging pawl between the recesses.

The operating-handle is preferably constructed of spaced cheek-plates 13 14, separated by a spacer member 15, the cheek-plate 13 having an open recess 16 and the cheek-plate 14 having an open recess 17, the spacer member 15 equaling in thickness the thickness of the member 10, so that when the three parts 13, 14, and 15 are united by rivets 18 or other suitable fastenings the recesses 16 17 may be engaged with the stock of the implement at each side of the member 10. The spacer member 15 is provided with an integral resilient pawl 19, adapted to engage the teeth of the member 10 when the connected cheek-plates 13 14 are disposed upon the stock, as above described. By this arrangement it will be obvious that when the handle is disposed upon the stock, as above noted, with the resilient pawl bearing against one of the teeth and the handle moved in one direction the pawl will "pick up" the member 10 and the stock to which it is attached and rotate it, and at the return stroke the resilient pawl will simply "click" over the teeth of the member 10 and not produce any effect thereon. By this simple means a very efficient ratchet implement is produced which may be inexpensively manufactured and employed in connection with a variety of implements.

The structure shown in Fig. 3 is provided at one end with a threaded recess 20, in which a handle 21 may be inserted or in which an adjusting-screw 22 may be inserted, as required, while the other end of the member 12 is provided with a socket 23, adapted to receive a drill, boring-tool, or other similar implement or to receive the stem of a socket-wrench 24. (Represented in Fig. 6.) The handle portion of the device being detachable and the toothed member 10

having its teeth alike on both sides, the handle member may be readily reversed in position upon the stock, and thus rotate the stock in either direction. The terminals of the hooks of the handle members are preferably inclined outwardly, as shown, to facilitate the placing of the implement upon the stock, as the outwardly-inclined terminals of the hooks prevent the latter from catching upon the toothed member.

Having thus described the invention, what is claimed as new is—

The combination with a stock having a disk provided with spaced peripheral teeth and extending laterally thereof, of an operating-handle comprising spaced plates having transverse recesses at their free ends with

the terminals of the portions of the plates exteriorly of the recesses curving outwardly in opposite directions to facilitate the engagement with the stock, and a spacer disposed between said plates and provided with an integral resilient pawl for yieldably engaging the teeth of said disk, said pawl being disposed at the closed ends of the transverse recesses in said spaced plates, and means for connecting said plates and spacer member.

In testimony that I claim the foregoing as my own I have hereto affixed my signature in the presence of two witnesses.

CLARENCE H. BILLINGS.
